United States Patent Office

Des. 196,087
Patented Aug. 20, 1963

196,087

SUBMARINE

Edmond Armstrong, Torrance, Calif., assignor to American Submarine Company, Cleveland, Ohio, a corporation of California

Filed Oct. 6, 1961, Ser. No. 66,987

Term of patent 14 years

(Cl. D71—1)

FIG. 1

FIG. 2

I claim:

The ornamental design for a submarine, substantially as shown.
